(73) Assignee: **Japan Servo Co., Ltd.**, Tokyo (JP)

(57) **CLAIM**

(***) Term: **14 Years**

(21) Appl. No.: **29/277,253**

(22) Filed: **Feb. 20, 2007**

The ornamental design for a part of a propeller for an axial flow fan, as shown and described.

DESCRIPTION

(30) **Foreign Application Priority Data**
Nov. 22, 2006 (JP) 2006-032008
(51) **LOC (8) Cl.** **23-04**
(52) **U.S. Cl.** **D23/413**
(58) **Field of Classification Search** D23/370,
D23/379, 413; 416/223 R, 238, 243, 179,
416/182; 361/695

FIG. 1 is a perspective view showing our new design;

See application file for complete search history.

FIG. 2 is a top view thereof;

FIG. 3 is a front view thereof;

FIG. 4 is a rear view thereof;

FIG. 5 is a bottom view thereof;

FIG. 6 is a left side view thereof; and,

FIG. 7 is a right side thereof.

The broken line showing of fan blades and a hub is included for the purpose of illustrating environmental structure and forms no part of the claimed design.
